GRAVITY DOWN STROKE PUMP

Hemer T. Lamb, Jr., Tulsa, Okla.

Application August 26, 1935, Serial No. 37,909

9 Claims. (Cl. 103—155)

This invention relates to well pumping apparatus and more particularly to a gravity down-stroke pump, especially for oil wells, to effect removal of oil from an oil bearing formation.

5 The principal object of the present invention is to provide a displacement pump of this character utilizing the weight of the rods, which is substantially greater than the weight of a column of fluid in the tubing, for forcing the well fluid to 10 the surface of the earth, in such a manner that the rod reciprocating mechanism at the top of the well is loaded with the weight of the rods only.

Further objects of the invention are to provide a pumping apparatus carried within the well tubing which may be removed from the well without the necessity of removing the well tubing; to provide a static fluid chamber of considerably greater capacity than the capacity of the working barrel whereby friction is substantially eliminated; to provide an effective exhaust for the apparatus of greater cross-sectional area than the working barrel of the pump, whereby back pressure against the pump is prevented; and to provide an efficient apparatus of this type.

25 In accomplishing these and other objects of the invention, I have provided improved details of structure, the preferred form of which is illustrated in the accompanying drawings, wherein:

30 Fig. 1 is a vertical elevation of my improved pump attached to the lower end of a well tubing, parts of the shell thereof being broken away to better illustrate the relative positions of the parts of the pump.

Fig. 2 is an enlarged vertical section of the 35 pumping apparatus showing the connection with the pumping rods, with the piston starting its up-stroke and the inlet valve in open position.

Fig. 3 is a vertical section showing the piston on its down-stroke with the oil inlet closed and 40 exhaust valves in open position.

Fig. 4 is an enlarged detail vertical section showing the pilot on the working barrel partly removed from its seating shoe.

Fig. 5 is a horizontal section on the line 5—5, 45 Fig. 2.

Fig. 6 is a horizontal section on the line 6—6, 46 Fig. 2.

Fig. 7 is a horizontal section on the line 7—7, 47 Fig. 2.

50 Fig. 8 is a horizontal section on the line 8—8, Fig. 2.

Fig. 9 is a vertical section through a well similar to Fig. 2, and showing a modified form of working barrel and piston.

55 Referring more in detail to the drawings:

1 designates a string of well tubing suspended by customary connections (not shown) at the head of a well hole 2 and extending approximately to an oil bearing formation 3. The lower end 4 of the tubing is externally threaded and attached thereto is an internally threaded collar 5. The collar suspends a nipple 6 by the externally threaded reduced upper end 7 of the nipple and a shell 8 is depended below the nipple 6 by means of an externally threaded collar 9 which engages the internal threads of the nipple and shell, the shell 8 containing my improved pumping apparatus.

10 designates an externally threaded cylindrical block to the lower end of which is attached the 15 shell 11 by internal threads at the upper end thereof. The shell 11 is comparatively long and extends downwardly in such a manner that a static fluid chamber 12 of considerable capacity is provided for containing oil pumped from the 20 formation as later described. The lower end of the shell 11 is internally threaded to receive the external threads of a plug 13 which is centrally bored, as at 14, and internally threaded at its lower end to receive the externally threaded 25 upper end of the screening device 15. The screening device 15 preferably comprises a perforated length of pipe having a closed end (not shown) which extends well within the oil bearing formation but which precludes entrance to the tubing of 30 matter foreign to oil.

The upper portion of the plug bore 14 is offset as at 16, to receive a valve seat ring 17 of the same inner diameter as the bore 14 and having a peripheral boss 18 adapted to seat on the upper end 35 of the plug. The valve seat is provided with an integral central bearing portion 19 connected with the valve seat ring 17 by radial arms 20, the bearing portion 19 being centrally bored to receive the valve stem 21 of a gravity valve 22. The 40 lower face of the valve 22 is tapered inwardly as at 23 to seat on a corresponding outward taper 24 at the upper end of the ring 17 and the valve and valve stem are held in operable position relative to the ring 17 by a nut 25 or the like on the 45 lower end of the valve stem. The plug 13 is additionally offset inwardly and threaded, as at 26, to receive an internally threaded collar 27 which fits over the valve seat ring 17 and has an inwardly extending boss 28 for clampingly engaging the 50 valve seat ring boss 18 to retain the valve seat within the plug.

The cylindrical block 10, a cross section of which is shown in Fig. 7, has apertures 29 for passing oil in a manner later described. The ap- 55

29 apertures **29** are threaded at their upper ends to receive individual externally threaded extensions **30** adapted to receive ball valve seats **31** fitting within the aperture extensions and having bosses **32** engaging over the upper end of the extensions **30**. The valve seats are centrally bored to a diameter sufficient to pass oil from the formation and yet seat ball valves **33**. Internally threaded ball valve cages **34** are screwed onto the aperture extensions **30**, the threads of the cages being sufficiently cut back from the interior of the cages to form shoulders **35** for retaining the valve seats **31** in position on the extensions. The valve cages are also provided with orifices **36** and **37** in such a manner that the cages may retain the ball valves in operable position and yet pass a quantity of oil sufficient to prevent any back pressure due to frictional influences of the flow of oil on the valves in relation to pressure behind the oil flowing through the valves.

The block **10** is also centrally bored, as at **38**, and internally threaded, as at **39**, to receive and retain a seating shoe **40**. The seating shoe **40** is inwardly tapered at its upper end, as at **41**, for guiding a pilot **42** to an enlarged pocket **43** at the lower end of the seating shoe, the pocket being inwardly tapered as at **44**, as best shown in Fig. 4, to retain the pilot in the shoe, as later described.

Suspended within the tubing **1** and connected to a suitable prime mover (not shown) at the head of the well is a string of rods **45** extending below the tubing into the sleeve **6**, as best shown in Figs. 2 and 3, and which is provided at its lower end with a squared internally threaded socket **46**. Threaded into the socket **46** is the externally threaded upwardly projecting end **47** of a valve cage **48** which is provided with orifices **49** for allowing escape of oil into the tubing, as later described. The lower end of the valve cage is internally threaded to receive an externally threaded lock nut **50** for retaining a valve seat **51** and ball valve **52** in position within the valve cage **49**. The lock nut **50** is centrally bored and threaded to receive an externally threaded hollow tube **53** which extends downwardly below the tubing rods and which is perforated as at **54**, for admitting oil to the tubing for a purpose later described. The tube **53** is externally threaded at its lower end to mount a lock nut **55** and a piston **56**.

The piston **56** comprises a cylindrical block of suitable metal which is tooled to provide a series of grooves for receiving alternate, slotted and preferably bronze rings **57** and movable steel inserts **58**. The bronze rings are slotted to provide for expansion and contraction and are held in position on the piston by a set screw (not shown) set into the piston. The rings are also positioned eccentrically on the piston so that a seal is always effected between the piston and the working barrel **59**. The steel inserts are loosely mounted on the piston between the bronze rings and are recessed on their inner surfaces to collect abrasive particles and other foreign matter accumulating on the piston.

The working barrel **59** comprises, in part, a stuffing box **60** which is centrally bored and internally threaded for slidably fitting over the perforated tube **53**. The bore of the stuffing box is provided with a packing gland **61** of suitable material which is held in position by a stop collar **62** adapted, by the upper externally threaded end thereof, to be screwed into the stuffing box **60**.

The stop collar **62** is provided with an enlarged circumferential boss, below the threads at its up-

per end, of the same diameter as the working barrel **59**, but is again reduced below the boss and threaded to receive the internal threads **63** of the upper end of the working barrel. The stop collar is further reduced and extended, as at **64**, to provide a sliding bearing surface for the piston tube **53** and a stop **64** at its lower end engageable by the lock nut **55** on the piston, when the tubing rods are raised above the normal stroke of the pump at the surface of the well, for removing the entire working barrel assembly.

The working barrel is further provided at its lower end with internal threads for receiving the external threads of the pilot **42**. The pilot is tapered inwardly as at **67** to seat in the outward taper **41** of the pilot shoe **40** and is then extended downwardly from the smaller diameter to terminate in an outwardly tapering flange **68** which, when the working barrel is lowered, is caught in the pocket **43** of the shoe. The pilot is slotted as at **69** to provide for compression thereof, in such a manner that as the inwardly tapered end **70** of the pilot is lowered into the shoe, the pilot will be compressed to smaller size. Upon continued lowering, however, into the pocket **43**, the pilot, being formed of a suitable spring steel, or the like, will resume its original shape to retain the pilot within the pocket by reason of the flange catching in the upper wall of the pocket.

The working barrel is retained in position with in the shell by the fingers **71** formed integrally with the sleeve **8** and extending radially inwardly thereof as shown in Fig. 5.

In assembling an apparatus constructed as described, the nipple and shell of the outer assembly **35** are connected with the well tubing, after which the exhaust valves are secured in their block, including the pilot shoe, and connected to the lower end of the shell. The static fluid chamber shell is then screwed onto the block and the bottom **40** plug and inlet valve screwed onto the static fluid chamber. The piston valve is then connected with the tubing rods and the perforated tube to the valve, after which the working barrel, including the stuffing box and stop collar, is sleeved **45** over the tube. The piston is then applied to the tube and the pilot finally screwed onto the lower end of the working barrel.

The operation of an apparatus constructed and assembled as described is as follows:

After assembling the outer shell, including the inlet and exhaust valves, on the well tubing, the tubing is lowered into the oil formation. The rods, including the working barrel and piston, are then lowered into the tubing and shell. As the lower end of the working barrel engages between the exhaust valves, the pilot will be compressed by pressure exerted by the weight of the rods on the corresponding tapers so that it may enter the pilot shoe, after which its resiliency causes it to **60** expand to its original shape to hold the working barrel in desired position within the shell.

The operating mechanism at the surface is then started to reciprocate the piston, which, on its up stroke creates a vacuum to draw oil from the formation to fill the static fluid chamber. Several strokes of the piston are required to fill the chamber, after which, upon each down stroke thereof, oil will be forced out the exhaust valves, through the tubing, and up to the surface where it can be collected and disposed of as desired. The rods are of substantially greater weight than the column of fluid in the tubing and it is, therefore, apparent that upon the down-stroke of the piston, the weight of the rods alone is sufficient to

raise a charge of well fluid in the tubing. It is also apparent that on the up-stroke of the piston the prime mover at the head of the well is required to lift only the weight of the rods and not the column of fluid as is the present practice. This construction eliminates expensive counter-balances and larger motors at the head of the well, which materially reduces installation and operating costs. It is also important to here point out that by providing the relatively large capacity of the static fluid chamber and an exhaust of greater capacity than the working barrel, friction and back pressure are materially reduced. It is apparent that the oil drawn from the formation will not immediately be forced through the exhaust valves by the piston, but that some subsequent stroke of the piston will effect removal of the oil formerly admitted to the chamber.

It sometimes happens that oil from the formation seeps up above the piston in the working barrel, but compression from this source is avoided by provision of the perforations in the tube, which admits the oil to the interior thereof and passes it upwardly to the ball valve for escape into the tubing and thence to the surface.

When it is desired to remove the working barrel and piston for repair, the tubing rods are removed from the pump and drawn upwardly. The upward pressure raises the piston in such a manner that the lock nut on the piston engages the stop collar on the working barrel to tend to raise the assembly. The upward pressure compresses the pilot to permit its removal from the shoe, after which the working barrel and piston may be drawn to the top of the well for repair or replacement.

In the form of the invention shown in Fig. 9, the working barrel 75 is screwed permanently into the central bore 76 of the member 10, and has a plain upper end 77 through which a plunger tube 78 reciprocates to actuate the piston 79 under influence of the rods 45. The tube 78 is of a suitable diameter to afford a sliding fit within the working barrel and has its upper end connected to the rods by means of a coupling 80 having apertures 81 therein through which the tube fills with well fluid. The lower end of the tube screws directly onto a threaded boss 82 on the piston. The tube is of sufficient length that when the piston is at the lower end of the working barrel the upper end of the tube projects therefrom. The tube and piston are thus guided the entire length of the barrel to prevent any buckling tendency in the barrel. Attention is here called to the fact that the effective diameters of the tube and piston are substantially that of the couplings for the rods so that there is no tendency to lift oil on the up-stroke of the piston. It is also apparent that with the tube 78 filled with well fluid, buoyancy is avoided and weight added to aid in the pumping operation on the down stroke of the piston.

From the foregoing it is apparent that I have provided an improved down-stroke gravity pump in which the weight of the rods is utilized to lift oil to the surface of the earth.

It is also apparent that I have provided a novel construction for materially reducing friction and back pressure from the pumping apparatus as well as providing a removable working barrel and piston assembly.

What I claim and desire to secure by Letters Patent is:

1. A well pumping apparatus including tubing, 75 a screened inlet valve at the bottom of the tubing,

an apertured block dividing the tubing into a fluid storage chamber and a fluid flow chamber and having a seating shoe, a working barrel mounted in the block having a pilot cooperable with the seating shoe for removably latching the working barrel in the block, rods in the tubing, a piston mounted on the rods and slideable in the working barrel, and valves in the block for passing fluid contained in the storage chamber to the flow chamber upon actuation of the piston. 10 5

2. A well pumping apparatus including tubing, well fluid inlet means at the bottom of the tubing, a block dividing the tubing into a fluid storage chamber and a fluid flowing chamber, a working barrel mounted in the block having substantially less capacity than the fluid storage chamber whereby friction of fluid against fluid is prevented, rods in the tubing, a piston mounted on the rods and slideable in the working barrel, valves in the block having greater effective area than 20 the working barrel for passing fluid contained in the storage chamber to the flow chamber upon actuation of the piston to prevent back pressure of fluid on the working barrel, and means on the working barrel and block for removably latching 25 the working barrel in the tubing.

3. A well pumping apparatus including tubing, a fluid inlet valve at the bottom of the tubing, a circularly apertured block dividing the tubing into a fluid storage chamber and a fluid flowing chamber, 30 a working barrel mounted in the block, rods in the tubing, a piston mounted on the rods and slideable in the working barrel, a circular series of valves cooperating with the apertured block for passing fluid contained in the storage chamber to 35 the flow chamber upon actuation of the piston, and compressible means on the working barrel cooperative with said block for removably latching the working barrel in the tubing.

4. A well pumping apparatus including tubing, 40 a screened fluid inlet gravity valve at the bottom of the tubing, a circularly apertured block dividing the tubing into a fluid storage chamber and a fluid flow chamber and having a seating shoe, a working barrel of substantially less capacity 45 than the fluid storage chamber whereby friction of fluid against fluid is prevented having a pilot removably engageable in the seating shoe, rods in the tubing, a piston mounted on the rods and slideable in the working barrel, and a circular series of valves in the block for passing fluid contained in the storage chamber to the flow chamber upon actuation of the piston of greater effective area than the working barrel for preventing back pressure of fluid on the working barrel. 55

5. A well pumping apparatus including tubing, well fluid inlet means at the bottom of the tubing, a block dividing the tubing into a fluid storage chamber and a fluid flowing chamber, a working barrel mounted in the block, rods in the tubing, 60 a piston mounted on the rods and slideable in the working barrel, valves in the block for passing fluid contained in the storage chamber to the flow chamber upon actuation of the piston, means on the working barrel and block for removably latching the working barrel in the tubing, and means for exhausting fluid seeping into the working barrel above the piston.

6. A well pumping apparatus including tubing, a screened well fluid inlet gravity valve at the 70 bottom of the tubing, a circularly apertured block for dividing the tubing into a static fluid storage chamber and a fluid flowing chamber, a working barrel mounted in the block having substantially less capacity than the storage chamber, rods in 75

- the tubing, a piston mounted on the rods and slideable in the working barrel, a circular series of valves cooperating with the apertured block for passing fluid contained in the storage chamber to the flow chamber upon actuation of the piston, means on the working barrel and block for removably latching the working barrel in the tubing, and means for exhausting fluid seeping into the working barrel above the piston.
- 10 7. A well pumping apparatus including tubing, a screened well fluid inlet gravity valve at the bottom of the tubing, a circularly apertured block dividing the tubing into a static fluid storage chamber and a fluid flowing chamber, a working barrel having a pilot and having substantially less capacity than the static fluid storage chamber whereby friction of fluid against fluid is prevented, rods in the tubing, a piston slideable in the working barrel, a hollow perforated piston rod connecting the piston with the rods, a circular series of valves cooperating with the apertured block for passing fluid contained in the storage chamber to the flow chamber upon actuation of the piston and having substantially greater effective area than the working barrel to prevent back pressure of fluid on the working barrel, and a valve at the upper end of the piston rod for exhausting fluid seeping into the working barrel and passing through said perforations above the piston to the tubing.
- 15 8. A well pumping apparatus including tubing, a fluid inlet valve at the bottom of the tubing, a circularly apertured block dividing the tubing into a fluid storage chamber and a fluid flowing chamber, a working barrel mounted in the block, rods in the tubing, a piston, a tubular plunger having a sliding fit within the working barrel for connecting the piston with the rods, means for admitting well fluid to said tubular plunger, and a circular series of valves cooperating with the apertured block for passing well fluid contained in the storage chamber to the flow chamber upon actuation of the piston.
- 20 9. A well pumping apparatus including tubing, a well fluid inlet gravity valve at the bottom of the tubing, an apertured block dividing the tubing into a static fluid storage chamber and a fluid flowing chamber and having a seating shoe, a working barrel having a pilot cooperable with said shoe for removably latching said working barrel in said block, said working barrel having substantially less capacity than the static fluid storage chamber whereby friction of fluid against fluid is prevented, rods in the tubing, a piston slideable in the working barrel, a hollow perforated piston rod connecting the piston with the rods, means cooperating with the apertured block for passing fluid contained in the storage chamber to the flow chamber upon actuation of the piston having substantially greater effective area than the working barrel, and means at the upper end of the piston rod for exhausting fluid seeping into the working barrel and passing through said perforations to the tubing.

HOMER T. LAMB, JR.
